International Precipitation Company, Los Angeles, Calif., a corporation of California

Application April 19, 1937, Serial No. 137,864
In Germany April 22, 1936

14 Claims. (Cl. 183—7)

The present invention relates generally to improvements in method and apparatus and for effecting the precipitation of suspended particles from a stream of gas and more especially to devices of this kind in which the particles are first charged in one field and then precipitated out in a second field. In precipitators of this latter type, the gas is first passed through a discharging or ionizing field in which the particles become 5 electrically charged, and then the gas is passed through a separate, non-discharging field in which precipitation of the particles takes place on one or more collecting electrodes.

In electrical precipitators as usually constructed, the gas stream flows past the electrode surfaces in a direction generally parallel thereto. The electrical field is maintained between the electrodes and so is more or less at right angles to the gas flow, which thus offers little or no assistance to the separation of particles from the gas but rather interferes with the separation since there is a tendency to pick up and carry along in the gas stream material that has been previously deposited.

It is a general object of our invention to provide a precipitator of increased efficiency and effectiveness which is simple and free of undesirable complexities.

It is also a principal object to provide a precipitator of the two-field type in which the gas stream and the precipitating field exert their forces in the same direction on the suspended particles and so reinforce each other in effecting precipitation of the particles.

A further object of our invention is to provide a precipitator of the two field type in which the precipitating field has a fluid pervious electrode through which gas passes to bring about intimate contact of the gas stream with the electrode and 40 completely precipitate suspended particles.

The method of operation of the invention comprises passing a stream of gas, containing suspended particles previously charged electrically, through a non-discharging precipitation field, 45 and maintaining the precipitation field in such a direction that the force it exerts on the suspended particles generally coincides with the direction of stream flow and so aids the movement of the particles toward the collecting electrode.

These objects are attained in a precipitator of our invention by providing a pair of electrodes, one of which is a discharge electrode, and between which is maintained an electric field of 55 the discharging or ionizing type; and a second

pair of non-discharging electrodes, one of which is fluid-pervious to permit the gas to pass therethrough, and between which is maintained an electrical field of a non-discharging type to precipitate the previously charged particles from the 5 gas stream. One electrode of each pair is maintained at a common polarity, and preferably at a common potential, while the other two electrodes are both of the opposite polarity but are not necessarily both at the same potential relative to the opposing member of their respective pairs. The precipitating field is maintained between the two electrodes of the second pair in such a direction that the force exerted by the 10 field on the suspended particles generally coincides with the direction of the gas flow through the pervious electrode, so that the electrical field and the gas flow reinforce each other in moving suspended particles.

How the above and other objects and advantages of our invention are secured will be better understood by reference to the following description and the annexed drawings in which:

Fig. 1 is a vertical section through a preferred form of precipitator illustrated somewhat diagrammatically;

Fig. 2 is a horizontal section on line 2—2 of Fig. 1;

Fig. 3 is a vertical section through a variational form of precipitator;

Fig. 4 is a vertical section through another variational form of precipitator; and

Fig. 5 is a fragmentary horizontal section through another variational form of precipitator in which all of the electrodes are arranged in a 35 single gas conduit.

The form of precipitator illustrated in Figs. 1 and 2 comprises housings 10 and 12, which are respectively the ionizing and precipitating units and are connected by conduit 13. Discharge electrode 14, such as a wire or small diameter rod, is mounted coaxially of housing 10, being supported and insulated from the housing at its upper and lower ends by means of insulators 16. Since housing 10 is grounded, as at 15, the housing and discharge electrode 14 constitute a pair of electrodes between which an ionizing field is maintained by means of high tension unidirectional current supplied to the discharge electrode from any suitable source by lead 17. The potential supplied to the electrodes in this ionizing field is sufficient to produce the well known corona or silent discharge from the discharge electrode, but is not sufficient to bring about a disruptive or spark discharge.

Within the precipitating unit is a central electrode 20 supported by means of insulator 21, which electrically insulates the electrode from housing 12, which is also grounded at 15. Although electrode 20 is here shown as circular in cross section with hemispherical ends, it may be of any other suitable shape having surfaces of relatively large radius so that discharge will not be produced. In order to decrease the weight, the electrode is preferably hollow. Surrounding and concentric with electrode 20 is a second electrode 23 attached to and supported by housing 12 and electrically grounded as by electrical connection to said housing, and made from a perforated plate or other foraminous material, such as a screen, which will permit the free passage of gas through the electrode. Electrode 23 is preferably of the same shape as electrode 20, but is open at its upper end to permit the introduction of gas as will be more fully explained. The pervious electrode 23 is spaced inwardly from the housing 12 to provide an annular passage 22 for carrying away the gas passing through said electrode. Electrodes 20 and 23 form the second pair of electrodes between which the precipitating field is maintained.

An annular chamber 25 is formed around the lower portion of housing 12 and communicates with the interior of the housing through a number of openings 26 through which gas may leave the housing and enter chamber 25 to reach discharge conduit 27 by means of which the cleaned gas is conveyed to a stack or other desired place. The precipitate collecting upon electrode 23 may be removed by any suitable means, such as rapping, and is prevented from entering openings 26 by means of a conical guard at 28. This precipitate falls to the bottom of the housing and may be removed from time to time by opening trap door 30 which also affords access to the interior of the precipitating unit.

A non-discharging electrical field is maintained between electrodes 20 and 23 by means of unidirectional current supplied over lead 24 at suitable high tension to the central electrode, the opposing electrode 23 being grounded through housing 12. It is preferred that housings 10 and 12 and electrode 23 are electrically connected together and grounded, and then they are always at a common potential and of one polarity. Electrodes 14 and 20 are both of a similar polarity, that is of the polarity opposite that of their opposing electrodes 10 and 23, respectively. However, the potential maintained between the electrodes of one pair is not necessarily the same as that between the other pair and the potentials may be varied independently of each other to obtain the best operating conditions. It is preferred, though not necessary, to maintain electrodes 14 and 20 at a negative potential with respect to their opposing electrodes so that the gases passing through the ionizing field have the suspended particles charged negatively.

The electrical apparatus may be varied as desired to suit operating requirements. As typical of preferred practice, but without limitation thereto, we show means for supplying the precipitator with rectified high tension alternating current. Alternating current is stepped up by a transformer 32 and then passed through a full wave rectifier 34. Each of leads 17 and 24 is connected to a separate rectifier since this permits different voltages to be applied to electrodes 14 and 20, thus affording flexibility in operation; but leads 17 and 24 may both be connected to the same source if desired, as mentioned below.

In operation, the stream of gas containing suspended particles to be removed enters the precipitator through inlet means 18 and flows upwardly and parallel to the surfaces of electrodes 10 and 14 so that the entire stream of gas passes through the ionizing field maintained between these two electrodes. The gas, now containing negatively charged particles, goes through conduit 13 to the interior of the fluid pervious electrode 23. Electrode 20 being negatively charged, repels the negatively charged particles suspended in the gas toward the positive electrode 23, so that the electrical field between these two electrodes is in substantially the same direction and in reinforcement of the flow of gas outwardly through fluid pervious electrode 23. The negatively charged particles come into contact with electrode 23, or housing walls 12, where they lose their charge and collect on the electrode surfaces, eventually accumulating in larger masses which fall off, or may be shaken off if necessary, and drop into the bottom of housing 12. The clean gases are then discharged from the precipitator through outlet means 27. The flow of gas is maintained by means not shown, but the gas is customarily under natural or forced draft.

Fig. 3 illustrates a variational form of precipitator constructed as in Fig. 1 except that the two pairs of electrodes are arranged one above the other and are joined together so that they are placed in end-to-end relation. In this form, housing 10a of the ionizing unit is mounted directly on housing 12a of the precipitating unit with the fluid pervious electrode 23a supported from housing 12a as before but placed with its open upper end in direct communication with housing 10a. From a single insulator 40 at the upper end of the ionizing unit is suspended the discharge electrode 14a and, below it, the central electrode 20a in such a way that electrodes 14a and 10a form the pair of electrodes between which an ionizing field is maintained, and electrodes 20a and 23a form the second pair of electrodes between which a non-discharging precipitating field is maintained.

The electrical connections differ only in that the single high tension lead 17 is necessary to both the electrodes 14a and 20a, since in this case these two electrodes are maintained at the same potential relative to their opposing electrodes 10a and 23a which are likewise both at a common potential. As before, the gas containing suspended particles enters through inlet means 18, passes downwardly through the ionizing unit 10a, where the particles become charged in the ionizing field, and then enters the precipitating field inside pervious electrode 23a in which the charged particles are forced outwardly toward electrode 23a by means of the field maintained between that electrode and central electrode 20a. The gas passes through the openings in electrode 23a and is discharged through outlet means 27, while the precipitated particles are removed from the bottom of housing 12a as described.

Another variational form is illustrated in Fig. 4. In this form of precipitator the ionizing unit 10 is constructed in the same way as described in connection with Fig. 1, but the construction of the precipitating unit is changed by making the inner electrode fluid pervious instead of the outer one, as in Fig. 1. In this case, the inner electrode 41 is shown as a cylindrical member of wire screen closed at its upper end by plate 42 and supported on insulators 43, which are in turn mounted upon housing 12b. Housing 12b

of the precipitating unit is reduced in diameter in its upper portion opposite inner electrode 41, so that the housing acts directly as the second electrode of this pair and the precipitating field 5 is maintained in the space between the outside of the electrode 41 and the inside of housing 12b.

The gas containing charged particles is introduced into the open lower end of electrode 41 by means of nozzle 44 connected to conduit 13. Electrode 41 is preferably provided at its lower end with a non-pervious section as shown at 45 which extends for some distance below nozzle 44 and is preferably constricted at the bottom as shown. By means of this construction gas issuing 10 from the nozzle is projected upwardly at a high velocity and is prevented by the constriction from passing out of the electrode except through the upper fluid pervious portion. If desired, the lower end of the electrode may be closed off entirely 15 by means of an insulating member that fills the gap between nozzle 44 and electrode section 45. But this is not necessary with the illustrated construction since substantially no gas escapes through the open lower end of the electrode.

Housing 10 and 12b both have ground connections 15 and hence are maintained at a common polarity and potential. Electrodes 14 and 41 are preferably at a negative potential with respect to 20 their opposing electrodes and may be supplied with a high tension current from separate sources, as illustrated in Fig. 1, or from a single source, as shown in Fig. 4. In the latter instance the electrical equipment includes a voltage divider 47 so 25 that a lesser voltage may be impressed upon electrode 41 than is applied to electrode 14, though both electrodes are of a common polarity, i. e. negative.

In the operation of this form, gas enters 30 through inlet means 18, passes upwardly through the ionizing unit 10 in which the particles become electrically charged and is then introduced inside fluid pervious electrode 41 by nozzle 44. The gas passing through the openings in electrode 41 35 enters a non-discharging field which carries the particles toward collecting electrode 12b, since electrode 41 is of the same polarity as discharge electrode 14, so that the precipitating field acts to reinforce the gas flow through the fluid pervious electrode. The precipitated material drops to the 40 bottom of housing 12b, while the cleaned gases are discharged through the open upper end 48 of the housing.

There is shown in Fig. 5 a simplified form of 45 precipitator in which all the electrodes are placed in a flue 50, typically of rectangular cross section. Discharge electrodes 51 extend across the path of the gas stream within the flue and are supported by suitable insulating means not shown. Electrodes 52 are placed between the discharge electrodes and are of sufficiently large diameter to prevent corona discharge from them. Electrodes 52 are connected directly to the walls of flue 50 and hence are grounded through ground connection 55 50. At a point in the flue removed from electrodes 51 and 52 and beyond them in the direction of the gas flow, a fluid-pervious non-discharging electrode 55 is mounted on insulators 56 which electrically insulate the electrode from the flue as well as provide mechanical support. Beyond electrode 55 is an opposing fluid-pervious non-discharging electrode 57 which is electrically connected to the walls of the flue and so is also grounded. While electrode 55 is indicated as 60 being a perforated plate and electrode 57 as being

wire screen, yet such perforated plates or screen may be used for either or both of these non-discharging electrodes.

An electrode 51 and an electrode 52 form a pair of electrodes between which an ionizing field is maintained by the application of high tension current to the discharge electrode by means not shown, but which may be similar to the devices previously described. Likewise, the application of high tension current to electrode 55 creates a non-discharging electric field between it and the opposing electrode 57. The gas containing suspended particles, moving toward the left as indicated by the arrow, first passes through the discharging or ionizing field between the pair of electrodes 51 10 and 52, so that the suspended particles become electrically charged. As these charged particles pass through electrode 55, which is charged at the same polarity as the particles, they are repelled from the electrode toward collecting electrode 57 15 so that the precipitating field acts to move the particles in the same direction as does the gas stream moving through electrodes 55 and 57. It will be noticed that the construction and operation of the precipitator shown in Fig. 5 is the same 20 as described in connection with the earlier figures, but with the addition that both electrodes of the second pair, between which the precipitating field is maintained, are fluid-pervious, whereas in the earlier figures one of these electrodes was non- 25 pervious.

Apparatus for carrying out the method of the invention including a discharge electrode, an intermediate fluid-pervious electrode through which the gas flows, and a collecting electrode which 30 may or may not be fluid-pervious, together with means for establishing a high potential ionizing field between the discharge and intermediate electrodes and a separate substantially non-discharging field between the intermediate and collecting 35 electrodes to effect precipitation of the charged particles, is described and claimed in our copending application Serial No. 137,865, filed April 19, 1937.

The term "non-discharging electrode", as used 40 herein, is intended to denote an electrode of such configuration as to substantially prevent or minimize corona discharge therefrom at elevated potentials below the potential at which disruptive discharge occurs.

Having described various embodiments of our 45 invention, it will be realized that changes in the shape, arrangement and construction of the various features of the precipitators may be made without departing from the spirit and scope of our 50 invention, and that the description and drawings are to be construed as illustrative of rather than descriptive upon the appended claims.

We claim:

1. In an electric precipitator in which the gas 55 to be cleaned is first passed through an ionizing field in which the suspended particles are charged and subsequently passed through a substantially non-discharging field in which precipitation of the charged particles is effected, the combination of a pair of opposing substantially non-discharging electrodes spaced from each other, at least one of the electrodes being fluid pervious to permit the stream of gas to pass through it, and means for establishing an electric precipitating field between 60 the two electrodes of such polarity that the field moves particles previously charged in an ionizing field in the same direction as the flow of gas through the pervious electrode.

2. In an electric precipitator in which the gas to

- be cleaned is first passed through an ionizing field in which the suspended particles are charged and subsequently passed through a substantially non-discharging field in which precipitation of the charged particles is effected, the combination of a non-discharging fluid pervious electrode through which the gas passes, an opposing non-discharging electrode spaced from the fluid pervious electrode, and means for establishing an electric precipitating field between the two electrodes of such polarity that the field moves particles previously charged in an ionizing field in the same direction as the flow of gas through the pervious electrode.
3. In an electric precipitator in which the gas to be cleaned is first passed through an ionizing field in which the suspended particles are charged and subsequently passed through a substantially non-discharging field in which precipitation of the charged particles is effected, the combination of a non-discharging fluid pervious electrode through which the gas passes, an opposing non-discharging electrode spaced from the fluid pervious electrode, both said electrodes being hollow and placed one within the other, and means for establishing an electric precipitating field between the two electrodes of such polarity that the field moves particles previously charged in an ionizing field in the same direction as the flow of gas through the pervious electrode.
- 30 4. In an electrical precipitation apparatus through which flows a stream of gas containing suspended particles to be removed, the combination of a pair of electrodes, one of which is a discharge electrode; means creating a high potential difference between said electrodes to establish an ionizing field; a second pair of electrodes, both of which are non-discharging and one of which is fluid pervious to permit flow of the gas through it; means creating a high potential difference between the electrodes of the second pair to establish a precipitating field; one electrode of each pair being maintained at a common potential and the other two electrodes being of the same polarity, the relative polarity of the electrodes of the second pair being such as to establish the precipitating field in a direction that reinforces the gas flow through the pervious electrode.
5. In an electrical precipitation apparatus through which flows a stream of gas containing suspended particles to be removed, the combination of a pair of electrodes, one of which is a discharge electrode; means creating a high potential difference between said electrodes to establish an ionizing field; a second pair of electrodes, both of which are non-discharging and one of which is fluid pervious to permit flow of the gas through it; means creating a high potential difference between the electrodes of the second pair to establish a precipitating field; one electrode of each pair being maintained at a common potential and the other two electrodes being of the same polarity, the relative polarity of the electrodes of the second pair being such as to establish the precipitating field in a direction that reinforces the gas flow through the pervious electrode carrying suspended particles to the other electrode of the second pair and to collect the particles thereon.
6. In an electrical precipitation apparatus through which flows a stream of gas containing suspended particles to be removed, the combination of a pair of electrodes, one of which is a discharge electrode; means creating a high potential difference between said electrodes to establish an ionizing field; a second pair of electrodes, both of which are non-discharging and one of which is

fluid pervious to permit flow of the gas through it; means creating a high potential difference between the electrodes of the second pair to establish a precipitating field; one electrode of each pair being maintained at a common potential and the other two electrodes being of the same polarity, the relative polarity of the electrodes of the second pair being such as to establish the precipitating field in a direction that reinforces the gas flow through the pervious electrode and to collect thereon suspended particles.

7. In an electrical precipitation apparatus through which flows a stream of gas containing suspended particles to be removed, the combination of a pair of electrodes, one of which is a discharge electrode; means creating a high potential difference between said electrodes to establish an ionizing field; a second pair of electrodes, both of which are non-discharging and at least one of which is fluid pervious to permit flow of the gas through it; means creating a high potential difference between the electrodes of the second pair to establish a precipitating field; the discharge electrode of the first pair and said fluid pervious electrode of the second pair being of the same polarity and the other two electrodes being maintained at a common potential, and the polarity of the electrodes of the second pair being such as to establish the precipitating field in a direction that reinforces the gas flow through said pervious electrode.

8. In an electrical precipitation apparatus through which flows a stream of gas containing suspended particles to be removed, the combination of a pair of electrodes, one of which is a discharge electrode; means creating a high potential difference between said electrodes to establish an ionizing field; a second pair of non-discharging electrodes, one of which is non-pervious and one of which is fluid pervious to permit flow of the gas through it; means creating a high potential difference between the electrodes of the second pair to establish a precipitating field; the discharge electrode of the first pair and the non-pervious electrode of the second pair being of the same polarity and the other two electrodes being maintained at a common potential, and the polarity of the electrodes of the second pair being such as to establish the precipitating field in a direction that reinforces the gas flow through the pervious electrode.

9. In an electrical precipitation apparatus through which flows a stream of gas containing suspended particles to be removed, the combination of a pair of electrodes, one of which is a discharge electrode; means creating a high potential difference between said electrodes to establish an ionizing field; a second pair of non-discharging electrodes comprising a central electrode of extended surface and an electrode surrounding and parallel to the central electrode, one of the electrodes of the second pair being fluid pervious to permit flow of the gas through it; means creating a high potential difference between the electrodes of the second pair to establish a precipitating field; one electrode of each pair being maintained at a common potential and the other two electrodes being of the same polarity, the relative polarity of the electrodes of the second pair being such as to establish the precipitating field in a direction that reinforces the gas flow through the pervious electrode.

10. An electrical precipitation apparatus through which flows a stream of gas containing suspended particles to be removed, having in com-

- bination a pair of electrodes comprising an inner discharging electrode and an outer non-discharge electrode surrounding the discharge electrode, so arranged that the gas flows generally parallel to the electrode surface; means for creating a high potential difference between said two electrodes to establish an ionizing field; a second pair of non-discharging electrodes of extended surface comprising an inner electrode and an outer surrounding electrode that is fluid pervious to permit gas flow therethrough; the inner electrodes of each pair being joined together and extending substantially, end-to-end with respect to each other, and the outer electrodes of each pair being likewise joined together and extending substantially end-to-end with respect to each other; 10 means for creating a high potential difference between the electrodes of the second pair to establish a precipitation field; the outer surrounding electrodes of each pair being both of one polarity and the inner electrodes being both of the opposite polarity whereby the precipitation field is of a direction to move charged particles toward the surrounding pervious electrode for collection thereon.
11. An electrical precipitation apparatus through which flows a stream of gas containing suspended particles to be removed, having in combination a pair of electrodes comprising an inner discharging electrode and an outer non-discharging electrode surrounding the discharge electrode, so arranged that the gas flows generally parallel to the electrode surfaces; means for creating a high potential difference between said two electrodes to establish an ionizing field; a second pair of non-discharging electrodes of extended surface comprising an inner electrode that is pervious to permit gas flow therethrough and an outer surrounding electrode that is non-pervious; means for creating a high potential difference between the electrodes of the second pair to establish a precipitating field; the outer surrounding electrodes of each pair being both of one polarity and the inner electrodes being both of the opposite polarity whereby the precipitation field is of a direction to force charged particles, after passing through the inner electrode, toward the outer electrode for collection thereon.
12. An electrical precipitation apparatus through which flows a stream of gas containing suspended particles to be removed, having in combination a pair of electrodes comprising an inner discharging electrode and an outer non-discharging electrode surrounding the discharge electrode, so arranged that the gas flows generally parallel to the electrode surfaces; means for creating a high potential difference between said two elec-
- todes to establish an ionizing field; a second pair of non-discharging electrodes of extended surface comprising an inner electrode and an outer surrounding electrode that is fluid pervious to permit gas flow therethrough; the inner electrodes of each pair being joined together and extending substantially, end-to-end with respect to each other, and the outer electrodes of each pair being likewise joined together and extending substantially end-to-end with respect to each other; 10 means for creating a high potential difference between the electrodes of the second pair to establish a precipitation field; the outer surrounding electrodes of each pair being both of one polarity and the inner electrodes being both of the opposite 15 polarity whereby the precipitation field is of a direction to move charged particles toward the surrounding pervious electrode for collection thereon.
13. A method of electrical precipitation of suspended particles from a gas stream, that comprises subjecting a gas stream containing suspended particles to the action of a corona discharge in a high potential field to electrically charge the suspended particles; and passing the 20 gas with the charged particles through a substantially non-discharging high potential field maintained between two opposing electrodes, in such a direction that the last mentioned field reinforces movement of particles by the gas 25 stream toward one of said opposing electrodes.
14. A method of electrical precipitation of suspended particles from a gas stream, that comprises subjecting a gas stream containing suspended particles to the action of a corona discharge in a high potential field to electrically charge the suspended particles; and passing the 30 gas with the charged particles through a substantially non-discharging high potential field maintained between two opposing electrodes of which 35 one has a polarity opposite to that of the charged particles, the flow of gas through the last-named field being in a direction toward said one electrode, and the relative polarity of the two electrodes being such as to move particles toward said 40 one electrode in reinforcement of the movement of the particles toward said one electrode by the 45 gas stream.
